UNITED STATES PATENT OFFICE

95,440

DESIGN FOR A DOOR PLATE OR THE LIKE

Louis A. Macklanburg, Oklahoma City, Okla.

Application February 13, 1935, Serial No. 55,430

Term of patent 14 years

To all whom it may concern:

Be it known, that I, Louis A. Macklanburg, citizen of the United States, residing at Oklahoma City, in the county of Oklahoma and State of Oklahoma, have invented a new, original, and ornamental Design for Door Plate or the like as shown in the accompanying drawing and described in the following specification.

I claim:

The ornamental design for a door plate or the like as shown.

LOUIS A. MACKLANBURG.
